UNITED STATES PATENT OFFICE.

HENRY M. REMY, OF CONSTANCIA, CUBA.

CANE-PLANTING MACHINE.

1,877,929.

Specification of Letters Patent.

Patented May 10, 1921.

Application filed February 28, 1919. Serial No. 279,709.

To all whom it may concern:

Be it known that I, HENRY M. REMY, a citizen of the United States, residing at Constancia, Island of Cuba, have invented certain new and useful Improvements in Cane-Planting Machines; and I do hereby declare the following to be a full, clear, and exact description of the invention, such as will enable others skilled in the art to which it appertains to make and use the same.

This invention relates to cane planting machines, and more particularly to a machine adapted for forming furrows and depositing therein at uniform intervals suitable lengths of seed cane.

One of the main objects of the invention is to provide a machine of the character stated having means for forming a furrow to receive the cane, means being provided for depositing fertilizer in the furrow formed and then dropping the lengths of cane and covering the same.

Another object is to provide a machine in which the cane may be dropped into the furrow immediately subsequent to forming thereof, this cane being quickly covered so as to be embedded in cool moist soil, thereby avoiding all drying out of the soil of the furrow or of the cane by lying in the sun, such as occurs in the present methods of hand planting in which the cane is first dropped in the furrows which have been previously formed, by hand, this cane being later covered after having been exposed to the sun for a considerable length of time.

A further object is to provide a comparatively simple and efficient machine of the character stated whereby the great loss of time and labor incident to hand planting may be eliminated, the furrow being formed and fertilized and the cane deposited and covered during a single trip of the machine along the furrow.

A still further and important object is to provide a conveyer the upper run of which is substantially horizontal, this conveyer being provided with a plurality of receiving pockets for the lengths of cane, these pockets having their rearward walls inclined downwardly in the direction of movement of the conveyer to facilitate placing therein of the seed cane.

Further objects will appear from the detailed description.

In the drawings:

Figures 1 and 1^a are a side view of the

planter taken from the right hand side of the machine as considered from the direction of movement thereof when in operation.

Fig. 2 is a transverse vertical section through the machine, taken forwardly of the front wheels and looking rearwardly.

Fig. 3 is a section taken substantially on line 3—3 of Fig. 1.

Fig. 4 is a vertical section through the lower portion of the conveyer.

Fig. 5 is a fragmentary detail of one of the cross bars of the conveyer and a frame for one of the pockets carried thereby, showing the guide strips for the conveyer.

Fig. 6 is a fragmentary section of the means for securing the pocket frame to the cross bar of the conveyer.

Fig. 7 is a detail section through the lower part of the conveyer.

Fig. 8 is a section through the fertilizer distributer and the operating means therefor, taken substantially on line 8—8 of Fig. 1.

Fig. 9 is a detail plan view of the connection for shifting the clutch for throwing the fertilizer distributer and the cane planting means into and out of operation.

Fig. 10 is a detail fragmentary section through the conveyer showing the means for guiding the same during downward travel thereof.

Fig. 11 is a detail of the lever for shifting the fertilizer distributer clutch and associated parts.

Fig. 12 is a detail section of the fertilizer distributer control clutch and associated parts.

Fig. 13 is a detail of the gear connecting and speed changing key.

Broadly stating, the machine comprises a wheel mounted supporting frame carrying at its forward end a furrow forming member, fertilizer distributing means positioned to deposit fertilizer in the furrow formed immediately subsequent to forming thereof, cane depositing means for depositing lengths of seed cane in the furrow after fertilizing thereof, and covering disks positioned at the rearward end of the machine for covering the cane thus deposited. The body of the frame of the machine is preferably of substantially rectangular shape being composed of the side sills 1 and 2 of channel construction, and the front and back end sills, respectively, of angle construction. The frame thus formed is reinforced by a plu-

rality of intermediate transversely extending brace bars 5, 6, and 7 secured to the side sills thus producing a very strong and rigid structure. At each corner of the frame thus formed is secured an angle upright 9. These uprights support a frame designated generally by 10 adapted to carry a canopy or covering for protecting the machine from the elements.

10 The forward portions of the side sills 1 and 2 are bent inwardly at a slight angle to provide forwardly converging beams 1^a and 2^a which are rigidly connected at their forward ends by a securing plate 11 thus forming a rigid substantially V-shaped plow supporting frame. Spaced hangers 12 are rigidly secured at their upper ends to the forward end portions of arms or beams 1^a and 2^a and depend vertically therefrom. These hangers are provided each with a longitudinally extending series of openings by means of which a clevis plate 13 may be adjustably secured between the hangers for attachment of traction means to the plow, the means employed being preferably a traction engine though any other suitable traction means may be used. Each of the hangers 12 is further provided, adjacent the lower end portion thereof, with an inner longitudinally extending series of openings by means of which the forward end portion of a plow beam 14 of suitable construction may be pivotally secured to the hangers for rocking movement about a horizontal axis, the point of attachment of the beam being readily adjusted to suit conditions. The inner portion of this beam fits snugly between vertical guide bars 15 which depend from and are rigidly secured to spaced transverse angle brace bars 16 and 17 rigidly secured at their ends to the beams 1^a and 2^a of the plow supporting frame. These bars act to prevent all looseness or lateral play of the plow beam and to guide this beam during lowering or raising of the plow, which is effected by means of a lifting and lowering arm 18 connected at its forward end by a chain 19 to plow beam 14 an appreciable distance inside of the pivotal mounting thereof, this arm being secured on an operating shaft 20 rockable in bearing blocks 21 secured to the brace bars 16 and 17. By rocking this shaft in proper direction, the plow may be readily moved into or out of operative position. The plow beam 14 carries at its inner end a plow 22 of the middle-burster type, this plow acting when lowered and the machine is advancing, to form a ditch or furrow in the well known manner.

60 Vertical channel bars 74 and 75 are secured to the sills 1 and 2, respectively, in rear of the axle 46, these bars being in alignment transversely of the frame. The channel bars receive the vertical arms of angle plates 76 which are secured to the ends of a

transverse channel bar 77. The channel bars 74 are each provided with a longitudinally extending series of openings adapted to receive securing bolts inserted therethrough and through openings provided in the vertical arms of the angle plates 76, by means of which channel bar 77 may be readily secured in vertical adjustment between the bars 74 and 75. This channel bar 77 is provided with rearwardly projecting attaching brackets 78 of channel construction secured thereto, these brackets receiving securing pins 79 inserted therethrough and through the forward ends of the arms 80 of a substantially V-shaped disk carrying frame indicated generally by 81. The rearward ends of arms 80 of the frame 81 are rigidly connected by a plate 82 secured thereto, this plate being provided with means to be later described for adjustably securing the disk supporting arms 83 thereto, these arms carrying covering disks 84 of well known construction rotatably mounted on the rearward ends of the arms in the usual manner, these disks being set at the proper angle for covering a furrow formed by the plow after the lengths of cane have been deposited in this furrow. The arms 80 of the disk supporting and attaching frame 81 are braced by the cross braces 85 secured thereto. A chain 86 is secured at its lower end to the cross braces at the point of intersection thereof, the upper end of this chain being secured to an arm 87 secured on the inner end of a shaft 88 rockably supported in brackets 89 secured to the transverse brace bar 8 and projecting rearwardly therefrom. By rocking the shaft 88 in the proper direction the frame 81 may be swung to move the disks 84 into or out of engagement with the ground.

A fertilizer container 108 is supported adjacent the forward portion of the frame by means of angle bars 109 secured to the lower arms of the transverse brace bars 3 and 5, a suitable opening being provided through the platform structure 73 for snugly receiving this container. Suitable agitators are provided within the container and are operated by means of gears inclosed by gear casings 110 secured to the bottom of the container. A Y discharge tube 111 communicates with the container 108 adjacent each end thereof and serves to conduct the fertilizer therefrom into a downwardly and rearwardly inclined discharge chute 112 which is positioned centrally of the machine and in alignment with the plow 22 so as to direct the fertilizer into the furrow formed. The fertilizer container and associated parts are of standard construction, that employed being preferably one manufactured by B. F. Avery & Sons of Louisville, Kentucky, and need not therefore be further described in detail. A fer-

tilizer distributor operating shaft 113 is rotatably supported in hangers 114 depending from the gear casings 110, this shaft being held against end play in one direction by a 5 split collar 115 secured thereon adjacent one of the hangers. The outer end portion of shaft 113 is supported by a bearing sleeve 116 secured to the lower flange of side sill 1. A clutch member 117 is loosely mounted on 10 the shaft, this clutch member being provided with an elongated neck 118 which receives the end portion of the shaft and is rotatable in the sleeve 116. A sprocket wheel 119 is secured on the outer end portion 15 of neck 118 of this clutch member closely adjacent the outer end of sleeve 116, the clutch member being positioned closely adjacent the inner end of this sleeve and coöperating with the sprocket to secure the 20 shaft 113 against longitudinal movement. Sprocket 119 is in alinement with a sprocket wheel 120 secured on the inner end portion of the hub 45^a of the other ground wheel 45, and these two sprockets are operatively 25 connected by a sprocket chain 121 passed about the same. A clutch member 122 is feathered on shaft 113 and is forced toward clutch member 117 by an expansion coil spring 123 mounted about the shaft and confined 30 between clutch member 122 and a collar 124 secured on the shaft. Clutch member 122, when in operative position, operates with clutch member 117 to cause rotation of shaft 113 during advancement 35 of the machine, in the well known manner. A bell crank lever 125 is rockably supported, for movement about a vertical axis, by an angle plate 126 secured to the inner face of sill 1. This bell crank is provided, at 40 the inner end of its inner arm 127, with a fork 128 which fits about the neck of clutch member 122 and is provided with inwardly projecting anti-friction rollers engaging into a peripheral groove 129 formed in the neck 45 of the clutch member for this purpose. The outer end of the outer arm 130 is connected by a link 131 to the lower end of a shifting lever 132 pivotally mounted for rocking movement about a horizontal axis on a supporting U bracket 133 secured to the web portion of sill 1. This hand lever is provided with a spring pressed detent 134 which coacts with a rack 135 mounted in front of the lever to secure this lever in 50 rocked adjustment in the well known manner, this detent being raised through the medium of a connecting rod 136 the upper end of which is secured to a latch lever 137 rockable upon shifting lever 132 adjacent 55 the hand hold at the upper end thereof. By rocking lever 132 in proper direction, the fertilizer distributor may be readily thrown into or out of operation, as desired.

A bevel-gear 138 is keyed on shaft 113 adjacent the split sleeve 115. This gear meshes 60 with a bevel pinion 139 secured on a stub shaft 140 rotatably supported in a sleeve 141 carried by a hanger 142 depending from the transverse brace bar 5 and rigidly secured thereto. The rearward end portion 70 of shaft 140 is rotatably supported by a bearing sleeve 142^a carried by a hanger 143 which depends from the brace bar 6 and is rigidly secured thereto. The shaft 140 will thus be rotated from the fertilizer distributor operating shaft 113 when the latter is thrown into operation. In order to transmit rotary movement from the shaft 140 to the conveyer driving shaft 150 there has been provided a variable speed gearing which 75 permits rotation of the shaft 150 to be controlled.

The conveyer drive shaft 150 extends rearwardly across the lower corner or apex of a substantially triangular conveyer casing 80 designated generally by 162, and the rearward end portion of this shaft is rotatably mounted in a bearing sleeve 163 provided at the lower end of a hanger 164 secured to the cross brace beam 7. The upper or body 85 portion of the conveyer casing 162 is of sheet metal construction and is supported by a suitable angle iron frame secured to uprights 165 secured to the brace beams 6 and 7, these uprights being disposed in pairs at each side 90 of the conveyer casing structure. An angle beam 166 is secured to the upper end of each pair of uprights, this beam being slightly inclined transversely of the machine frame. A bearing block 167 is secured on the upper 95 flange of each beam 166 adjacent the upper end thereof. These blocks are disposed in alinement transversely of the conveyer casing and rotatably support a shaft 168 adjacent each end of which is secured a sprocket 100 wheel 169. A bearing block 170 is slidably mounted upon each of the beams 166 adjacent the lower end thereof, this block being adjusted toward the outer end of the beam by means of an adjusting screw 171 bearing 105 against the inner end of the block and threaded through a bracket 172 secured on the upper face of the beam. These bearing blocks 170 rotatably support a shaft 173 adjacent each end of which is secured a sprocket wheel 174. The sprocket wheels 169 and 174 are disposed in triangular arrangement with similar sprocket wheels 175 secured on shaft 150 adjacent 110 each side of the conveyer casing, and these sets of triangularly arranged sprocket wheels receive sprocket chains 176 passed thereabout, these chains being of any suitable or standard construction, the chain preferred being that chain known as No. 42, 115 made by the Link Belt Company of Philadelphia. The two chains 176 are connected by a canvas strip 177, this strip serving to close the space between the chains so as to provide an endless conveying belt. The 120 125 130

tension of this belt, may be readily adjusted to suit conditions by adjusting the shaft 173 toward or away from shaft 168 through the medium of the adjusting screws 171.

5 The chains 176 are connected by a plurality of equally spaced angle bars 178 secured thereto. Each of these bars is provided, at each end, with an extension 179. The rearward extension 179 of these bars, 10 of the upper run of the conveyer, are adapted to slidably engage the upper face of an angle guide and supporting strip 180 supported in substantial parallelism with the beam 166 by means of supporting brackets 181 secured to the beam and to the strip. The forward extensions 179 of the bars on the upper run of the conveyer are adapted to engage between two parallel angle guide strips 182 and 183 supported in 15 substantial parallelism with the other beam 166 by means of supporting brackets 184 secured thereto and to the beam. In this manner, the upper run of the conveyer is supported during operation thereof 20 and is held against all looseness or sagging. Spaced angle guide strips 185 and 186 are supported in the left hand arm, as considered from the direction of travel of the machine, of the conveyer casing by the brace beams 6 25 and 7 and uprights 165. The upper end portion of the outer strip 185 is turned outwardly as at 185^a so as to facilitate entry of the end portions 179 of the cross bars between these strips. These strips act to support the downwardly moving or left hand 30 run of the conveyer so as to effectually prevent looseness or sagging thereof, thus insuring accuracy of operation.

A substantially U-shaped frame 187 is 35 secured to the outwardly projecting arm 178^a of each of the bars 178 by means of securing straps 188 secured about the inner end portion of the end arm 189 of the frame, the lower portion of this arm being slightly 40 flattened as shown to prevent twisting or looseness. A sheet metal sleeve 190 is secured about the bight portion 191 of the frame and is provided with an inwardly projecting flange 192, similar sleeves 193 45 having inwardly projecting flanges 194 being secured about the end bars 189 of the frame. These sleeves and the flanges thereof serve to support the outer edge and end portions of a canvas covering or closure 50 member 195 for the frame 187, the inner edge portion of this canvas being secured to the outwardly projecting arm 178^a of bar 178. As will be noted, the body portion of the frame 187 is disposed at an obtuse angle to the 55 outwardly projecting arm of bar 178, and is so directed that the frames on the upper run of the conveyer are inclined downwardly in the direction of travel of the conveyer, the frames on the downwardly 60 moving or left hand run of the conveyer be-

ing disposed substantially horizontal. As will be noted more clearly from Figs. 3, 4 and 5, of the drawings, the top of the conveyer casing is open thus permitting the lengths of seed cane to be readily placed in 70 the pockets formed by the frames 187 and the canvas coverings therefor by an operator standing upon the platform structure 173. In practice, the cane is cut into pieces substantially eighteen inches long so as to 75 insure at least three eyes or nodes to each piece of cane, the cane stalks which vary in length from six to twelve feet being divided into sections by joints or nodes which are spaced from three to six inches apart. 80 These pieces of seed cane are placed in suitable trays, these trays being then stacked upon the platform structure as indicated in Figs. 1 and 1^a of the drawings, the seed cane being thus placed within easy reach of the 85 operator so as to be readily placed by him in the pockets of the upper run of the conveyer. The downward inclination of the frames 187 in the direction of the travel of the conveyer greatly facilitates insertion of the 90 pieces of seed cane into the pockets, as will be appreciated, thus effecting a material saving in both time and labor.

The lower section of the conveyer casing 162 is supported by angle iron frames 196 95 and 197 depending from the brace beams 6 and 7 and rigidly secured thereto. These frames support at their lower ends a substantially rectangular or box-like discharge tube 198, and the frames 197 are each provided with an intermediate outwardly arched portion 199, an offset portion 200 contiguous thereto, and a downwardly and 100 inwardly inclined portion 201 extending from the lower end of portion 200 to discharge tube 198. The lengths of seed cane supported within the pockets of the conveyer will rest upon the upper surfaces of the frames 187 during downward movement thereof, these frames being disposed at a 110 slight downward and inward inclination so that the piece of cane supported by any particular frame will be positioned at the angle of the end arms thereof. The outwardly arched portion 199 formed in the conveyer 115 casing accommodates the slight outward movement of the cane carrying frames during the travel thereof about the sprocket wheels 175. As the frame moves about the sprocket wheel, it is tilted downwardly so 120 as to cause movement of the cane supported thereby downwardly and outwardly, the piece of cane dropping into the offset portion of the conveyer formed by the portion 200 of frame 197, and being directed by the lower inclined portion 201 into the discharge tube 198. After the cane has been discharged from the supporting frame 187 of the pocket in which the cane was originally placed, this frame is moved upwardly by 125 130

the operation of the conveyer in the other or right hand side of the conveyer casing which, as will be noted, is enlarged to accommodate looseness or slack in the right hand run of the conveyer. The piece of cane which has been discharged falls through the tube 198 into a downwardly and rearwardly inclined discharge chute 202 which is hingedly secured at the upper edge 10 of its bottom wall to the forward wall of tube 198, by means of a hinge member 203. As will be noted, the cane conveyer is so disposed that the piece of seed cane which is discharged from a pocket thereof will be 15 disposed longitudinally of the machine when discharged into the chute 202, this chute acting to direct the pieces of seed cane into the furrow which has been previously formed and fertilized, it being understood 20 that the chute is in alignment longitudinally of the machine with the plow and the fertilizer discharging chute. This insures that the pieces of seed cane will be deposited at proper intervals and will be laid lengthwise 25 of the furrow formed, these pieces being covered immediately subsequent to depositing thereof by the covering disks. This insures that the seed cane will be planted in cool moist earth and that all drying of the 30 cane or of the soil of the furrow, such as occurs where hand planting is employed, is eliminated, thus insuring quick and strong germination of the cane.

Downward movement of the discharge chute 202 about its hinge axis is positively limited by means of supporting rods 204 which are pivotally secured at their lower ends to the side walls of the chute. These rods are provided in their upper portions 40 with longitudinally extending slots which receive screw studs 205 secured through the sides of the supporting frame for the discharge tube 198, wing nuts 206 being threaded upon these studs and serving to readily 45 secure the chute in adjusted position. This renders it possible to quickly and easily vary the inclination of the chute to suit conditions, while positively securing the chute in adjusted position. It will be understood, of course, that any other suitable or equivalent 50 form of supporting and adjusting means for the discharge chute 202 may be employed.

For containing the lengths of seed cane I employ canvas trays such as those illustrated 55 in Figs. 1 and 1^a. It is very desirable that these trays be of great strength while being as light as possible, in order to support the cane when the trays are stacked upon the platform of the planter as indicated in Fig. 60 1^a, while preventing all crushing or injury to the cane. This tray is of substantial rectangular shape. In practice, the lengths of seed cane are placed in these trays, the trays being then stacked upon the platform structure 65 of the machine in position to be easily

reached by an operator standing thereon, the operator removing the lengths of seed cane manually from the trays and placing the same in the upper run of the conveyer in the manner previously described, these lengths 70 of cane being deposited in the furrow formed and then covered by the covering disks.

It will be evident that there may be slight changes made in the construction and arrangement of the details of my invention 75 without departing from the field and scope of the same, and I intend to include all such variations, as fall within the scope of the appended claims, in this application in 80 which a preferred form only of my invention is disclosed.

What I claim is:

1. In a cane planting machine, a supporting frame, a cane conveyer casing extended 85 transversely of the frame and of triangular form which apex is directed downwardly, an endless conveyer within said casing, said casing having an open upper side and an open lower side, said endless conveyer comprising 90 a pair of chains, sprocket wheels for said chains, transverse members connecting said chains at spaced intervals, angularly extended bars carried by said transverse members, a pocket member carried by each of 95 said transverse members to form a pocket wall for a pocket carrying a section of cane to be dropped from the lower end of the casing, and a guiding discharge member extended from the lower end of said casing. 100

2. In a cane planting machine, a rectangular frame, a triangular conveyer casing mounted on said frame and having its apex directed downwardly and open, the upper side of said casing being open, a conveyer within said 105 casing, mounting means for said conveyer, said conveyer including chains and transverse connecting links, bar frames mounted on said plates and having their main portions bent at an acute angle thereto, transverse pocket members mounted on said frame so as to carry cane sections to the lower end of said casing, and rearwardly directed and downwardly inclined discharge means connected with the lower end of said 110 casing. 115

3. In a cane planting machine, a supporting frame, a conveyer casing mounted transversely of said frame and having a reduced lower end, the lower and upper ends of the 120 conveyer casing being open, an endless conveyer mounted in said conveyer casing, corner sprocket wheels mounted in the upper and lower sides of said casing for said conveyer, said conveyer including sprocket 125 chains engaged around said sprocket wheels, transverse connecting plates for said chains, frame members composed of bars of substantially U-shaped form having the ends of their legs mounted on said transverse plate, 130

the main portions of said frame being bent at an angle in one direction, flexible members secured to said frame members, and said transverse connecting plates thereby forming pockets between said frame members to receive cane sections to be planted, a downwardly and rearwardly inclined discharge spout extended from the lower open end of said conveyer frame, and means for connecting said spout.

4. In a cane planting machine, a supporting frame, a conveyer casing mounted transversely of the supporting frame and of triangular form, said conveyer casing having an open upper portion and an open lower end, an endless conveyer within said conveyer casing, upper sprocket wheels for said endless conveyer, the lower sprocket wheel for said endless conveyer, said conveyer and said conveyer casing being of triangular form, the apex of the casing being directed downwardly, guide members within said casing for said conveyer, said conveyer including sprocket chains engaged around said sprocket wheels, transverse connecting plates extended between said chains and having projecting end portions adapted to ride in said guides, pockets formed on said conveyer by means of frame members having bent end portions secured to said transverse connecting plates, transverse members secured on said frame members to form the movable walls of said pockets, the sides of the casing serving as side walls for said pockets, a discharge spout extended rearwardly and downwardly to carry cane sections from the conveyer to a furrow beneath said frame, and means for clamping said discharge spout to the lower end of said conveyer casing.

5. In a cane planting machine, a supporting frame, a cane conveyer casing extended transversely of the frame and of triangular form which apex is directed downwardly, an endless conveyer within said casing, said casing having an open upper side and an open lower side, said endless conveyer comprising a pair of chains, sprocket wheels for said chains, transverse members connecting said chains at spaced intervals, angularly extended bars carried by said transverse members, a pocket member carried by each bar to form a pocket wall for a pocket carrying a section of canes to be dropped from the lower end of the casing, a guiding discharge member extended from the lower end of said casing, and operating means for the conveyer.

6. In a cane planting machine, a rectangular frame, a triangular conveyer casing mounted on said frame and having its apex directed downwardly and open, the upper side of said casing being open, a conveyer within said casing, mounting means for said conveyer, including chains and transverse

connecting links, bar frames mounted on said links and having their main portions bent at an acute angle thereto, transverse pocket members mounted on said frame so as to carry cane sections to the lower end of said casing, rearwardly directed and downwardly inclined discharge means connected with the lower end of said casing, and operating means for the conveyer.

7. In a cane planting machine, the supporting frame, a conveyer casing mounted transversely of said frame and having a reduced lower end, the lower and upper ends of the conveyer frame being open, an endless conveyer mounted in said conveyer casing, corner sprocket wheels mounted in the upper and lower sides of said casing for said conveyer, said conveyer including sprocket chains engaged around said sprocket wheels, transverse connecting plates for said chains, frame members composed of bars of substantially U-shaped form having the ends of their legs mounted on said transverse plates, the main portions of said frame being bent at an angle in one direction, flexible members secured to said frame and said transverse connecting plates thereby forming pockets between said frame members to receive cane sections to be planted, a downwardly and rearwardly inclined discharge spout extended from the lower open end of said conveyer frame, means for connecting said spout to said conveyer, and operating means for the conveyer.

8. In a cane planting machine, a supporting frame, a conveyer casing mounted transversely of the supporting frame and of triangular form, said conveyer casing having an open upper portion and an open lower end, an endless conveyer within said conveyer casing, upper sprocket wheels for said endless conveyer, the lower sprocket wheel for said endless conveyer, said conveyer and said conveyer casing being of triangular form, the apex of the casing being directed downwardly, guide members within said casing for said conveyer, said conveyer including sprocket chains engaged around said sprocket wheels, transverse connecting plates extended between said chains and having projecting end portions adapted to ride in said guides, pockets formed on said conveyer by means of frame members having bent end portions secured to said transverse connecting plates, transverse members secured on said frame members to form the movable walls of said pockets, the sides of the casing serving as side walls for said pockets, a discharge spout extended rearwardly and downwardly to carry cane sections from the conveyer to a furrow formed beneath said frame, means for clamping said discharge spout to the lower end of said conveyer casing, and operating means for the conveyer.

9. In a cane planting machine, a supporting frame, a triangular conveyer casing mounted transversely of said supporting frame with the apex of the casing directed 5 downwardly, a conveyer within said conveyer casing, said conveyer casing having an open upper side, said conveyer casing having an open lower end, said open lower end of the casing having a depending portion, the discharge spout for said casing, means for clamping said discharge spout to said casing to receive the cane sections delivered thereto from the conveyer and turned to be deposited in longitudinal position 10 within a furrow formed by said machine, means for clamping said discharge spout on to the lower end of the conveyer casing, and operating means for said conveyer and operating mechanism for said conveyer.
10. In a cane planting machine, a supporting frame, a triangular conveyer casing mounted transversely of said supporting frame with the apex of the casing directed 15 downwardly, a conveyer within said conveyer casing, said conveyer casing having an open upper side, said conveyer casing having an open lower end, said open lower end of the casing having a depending portion, the discharge spout for said casing, means for clamping said discharge spout to said casing to receive the cane sections delivered thereto from the conveyer and turned to be deposited in longitudinal position 20 within a furrow formed by said machine, means for clamping said discharge spout on to the lower end of the conveyer casing, and operating means for said conveyer and operating mechanism for said conveyer.
10. In a cane planting machine, a supporting frame, a triangular conveyer casing mounted transversely of said supporting frame with the apex of the casing directed 25 downwardly, a conveyer within said conveyer casing, said conveyer casing having an open upper side, said conveyer casing having an open lower end, said open lower end of the casing having a depending portion, the discharge spout for said casing, means for clamping said discharge spout to said casing to receive the cane sections delivered thereto from the conveyer and turned to be deposited in longitudinal position 30 within a furrow formed by said machine, means for clamping said discharge spout on to the lower end of the conveyer casing, and operating means for said conveyer and operating mechanism for said conveyer.

livered thereto from the conveyer and turned to be deposited in longitudinal position within a furrow formed by said machine, means for clamping said discharge spout on to the 35 lower end of the conveyer casing, and operating means for said conveyer.

11. In a cane planting machine, a supporting frame, a conveyer casing mounted transversely of said supporting frame and 40 having a depending open end, said casing having an inclined open upper side, a conveyer within said conveyer casing, said conveyer being adapted to receive cane sections in pockets formed therein as the pockets 45 pass along the open upper side of the casing, a discharge spout for the lower open end of the conveyer casing, means for connecting said discharge spout to said casing, means for adjusting the incline of said discharge spout, said discharge spout being formed and positioned so as to receive the cane sections and deliver the same to a furrow with the cane sections turned for longitudinal positioning within the furrow and 50 means for operating said conveyer.

In testimony whereof I affix my signature in presence of two witnesses.

HENRY M. REMY.
